BUOYANT INFANT SEAT

Margaret J. Waters, 809 Rural Ave., R.R. 1,
Decorah, Iowa 52101

Filed Feb. 8, 1971, Ser. No. 113,778

Term of patent 7 years

Int. Cl. D21—03

U.S. Cl. D71—1

FIG. 1 is a frontal perspective view of a buoyant infant seat showing my new design;

FIG. 2 is a top plan view thereof;

FIG. 3 is a side elevational view as viewed from the bottom of FIG. 2;

FIG. 4 is a front elevational view; and

FIG. 5 is a rear elevational view thereof.

I claim:

The new and ornamental design of a buoyant infant seat, substantially as shown.
